UNITED STATES PATENT OFFICE.

CYRUS LEVI BUCKWALTER AND WILLIAM GUNN WIRT, OF LOUDONVILLE, OHIO.

DENTAL PLATE.

SPECIFICATION forming part of Letters Patent No. 781,589, dated January 31, 1905.

Application filed May 17, 1904. Serial No. 208,360.

To all whom it may concern:

Be it known that we, CYRUS LEVI BUCKWALTER and WILLIAM GUNN WIRT, citizens of the United States, residing at Loudonville, in the 5 county of Ashland and State of Ohio, have invented certain new and useful Improvements in Dental Plates, of which the following is a specification, such as will enable those skilled in the art to which it appertains to make and 10 use the same.

This invention relates to dental plates used in the manufacture of artificial teeth and to which the upper teeth are secured; and the object of the invention is to provide improved 15 means for holding such plates in position within the mouth.

The invention is fully disclosed in the following specification, of which the accompanying drawings form a part, in which the separate 20 parts of our improvement are designated by suitable reference characters in each of the views, and in which—

Figure 1 is a perspective view of our improved dental plate; Fig. 2, a longitudinal section thereof on the line 2 2, and Fig. 3 a transverse section thereof on the line 3 3.

In the practice of our invention we provide a dental plate α , composed of rubber or other suitable material in the usual manner and with 25 which in practice the teeth α^3 are connected. The body portion α^2 of the plate α is convex in cross and longitudinal section, as clearly shown in the drawings, so as to enable the said body portion to conform to the roof or palatine portion of the mouth, and said plate is 30 also provided with the usual flange or rim α^4 , forming a groove or space α^5 , in which the gums of the upper jaw fit.

In the practice of our invention and in order 35 to provide means to securely hold the plate α in the mouth we form in the upper surface of the central or body portion thereof a recess b , which is substantially of the same form as said plate, and in the central portion 40 of this recess we secure a suction device c , which is cup-shaped in cross-section and the general form of which is that of the recess b and the body portion of the plate. The suction device c is composed of pure soft rubber

and may be expanded and depressed by pressure applied to the perimeter thereof, so as to rest in or lie in the recess b and substantially fill the same.

In the form of construction shown a metal plate d is secured in the central part of the body portion α^2 of the plate α , and a small disk or button e is secured centrally in the bottom of the suction device c , and the plate d and disk or button e are connected by a pin or rivet f . In this way the suction device c is securely held in its proper position, and no part of the pin or rivet f can come in contact with the palatine surface of the mouth or with the tongue.

In practice the plate is inserted into the mouth in the usual manner and pressed upwardly, so that the cup-shaped suction device comes in contact with the roof or palatine surface of the mouth, and pressure is applied to the plate until it is firmly seated. In this operation the cup-shaped suction device is expanded, and all air is forced from between the same and the roof of the mouth. It will be understood that the perimeter of the suction device comes in contact with the roof of the mouth before the other portions of the plate, and by applying pressure to the plate and forcing it upwardly the cup-shaped suction device is expanded, as hereinbefore described, until it fills the chamber or recess b . In this position of the parts the cup-shaped device c forms or produces a suction which securely holds the plate in position, and said plate will not accidentally drop out and is held against any lateral or other movement.

Our improved suction device or attachment also prevents all soreness in the roof of the mouth, and coughing, laughing, or speaking will not loosen or detach the plate, and this gives great confidence to the user thereof and also prevents to an extent the breaking of the plate from any cause.

Having fully described our invention, what we claim as new, and desire to secure by Letters Patent, is—

A dental plate of the usual form, the body portion of which is provided in the top thereof with a recess, and a flexible and elastic cup-

shaped suction device secured centrally in said recess and the edges of which are directed upwardly, the connection of the suction device with the plate being made by means of a pin 5 or rivet having end pieces, one of which is countersunk in the central top portion of the top plate and the other in the central bottom portion of the suction device, substantially as shown and described.

In testimony that we claim the foregoing as 10 our invention we have signed our names, in presence of the subscribing witnesses, this 14th day of May, 1904.

CYRUS LEVI BUCKWALTER.
WILLIAM GUNN WIRT.
